Dec. 1031

R. Ham. of Troy, N. Y.

Assignor to

Smith, Sheldon & Co. of same place.

Letters Patent. No. 1031. dated Aug. 3, 1858.

The schedule referred to in these Letters Patent and making part of the same.

To all whom it may concern:

Be it known that I, Robert Ham, of the City of Troy, in the County of Rensselaer, and State of New York, have invented or produced a new and ornamental Design for Plates of a Cooking Stove, called the "Emporium," and I do hereby declare that the following is a full and exact description of the same, reference being had by the letters to the annexed photographic drawings making a part of this specification, in which

Fig. 1. represents the top-plate of the Stove.

Fig. 2: the hearth plate.

Fig. 3. a foot.

Fig. 4. a large oven door.

Fig. 5. a small oven door.

Fig. 6. the door or panel at each end of the fire-box; and

Fig. 7. a door in front of the fire-box.

My design for the top-plate, A, consists of the grooved concave border molding, a, with the ornaments b, arranged thereon as shown in Fig. 1. My design for the hearth plate B, consists of the concave border molding, c, with the ornaments d, arranged thereon as represented in Fig. 2. My design for the foot, C, consists of the waving striated surface, e, — surrounded by the sinuate leaves f, as shown in Fig. 3. My design for the

large oven door, D, consists of the convex surface *g* of waved striae, the ornamental molding *h*, and the compound molding, *i*, with the scroll leaves, *j*, in its corners, all disposed upon the plate in the manner shown in Fig. 4. My design for the small door, E, of the oven consists of the central convex lace-work surface, *K*, the ornamental molding, *l*, and the compound molding *m*, having the scroll leaves, *n*, in its corners, all arranged upon the plate as shown in Fig. 5. - My design for the door or panel F, at the end of the fire box, consists of the central raised lace-work surface, *o*, the surrounding ornamental covering, *p*, and the scroll leaves, *r*, all placed together on the plate as shown in Fig. 6. - My design for the front door, G, of the fire box, consists of the flat surface, *S*, of waved striae, and the compound border molding *t*, with the leaves *u*, all disposed as shown in Fig. 7.

What I claim as my invention or production, and desire to secure by Letters Patent is the ornamental design of the plates or castings A, B, C, D, E, F, and G, of a Cooking Stove, as herein described and represented in the annexed photographs.
